DOMINICK LUSSETTO AND JAMES FASSERO, OF OSHKOSH, NEBRASKA

SLIDING-DOOR LATCH

Application filed October 25, 1928. Serial No. 315,011.

The invention relates to latch mechanisms for self-closing sliding doors, and in the present disclosure, the improved latch means is shown in connection with a safety bullet-proof door for bank cages, the door being hereinafter referred to as a barrier.

Heretofore, latch mechanisms for holding self-raising barriers in lowered position, have been very complicated and expensive and have usually entailed the provision of a number of parts above the floor. It is the object of our invention however, to provide an exceptionally simple and inexpensive latch means which embodies no portions above the floor except a releasing stud or studs to be foot-operated.

With the foregoing in view, the invention resides in the novel subject matter herein-after described and claimed, description being accomplished by reference to the accompanying drawings.

Fig. 1 is a vertical longitudinal sectional view on line 1—1 of Fig. 2.

Fig. 2 is a horizontal sectional view on line 2—2 of Fig. 1.

Fig. 3 is a view similar to a portion of Fig. 1 but showing the barrier raised and the switch for the alarm closed.

Fig. 4 is a vertical transverse sectional view on line 4—4 of Fig. 1.

Fig. 5 is a view similar to Fig. 4 but showing the barrier raised.

Fig. 6 is a detail vertical section on line 6—6 of Fig. 4.

Fig. 7 is an outer cage wall 7 is shown, embodying end posts 8, a lower bullet-proof portion 9 and an upper openwork portion 10, the usual counter or the like 11 being behind this portion.

The posts 8 are provided with longitudinal channels 12 and a normally lowered, bullet-proof barrier 13 is slidable at its ends in these channels, its upper edge being normally about flush with the counter 11. Coiled tension springs 14 are shown within the channels 12 connected at their lower ends with projections 15 on the barrier 13 while their upper ends are anchored, for instance, by adjustable anchors 16.

A hook 17 is secured to and projects down-

wardly from the barrier 13 through an opening 18 in the cage floor 19. Extending horizontally under this floor, is an elongated bar 20 having one end 21 which overlies the hook 17 to hold the barrier 13 normally against ascent. This end of the bar is provided with a downwardly projecting arm 22 which is preferably inclined. The lower end of this arm is pivotally supported at 23 and in the present showing, this pivoted end of said arm, 55 extends between two fixed horizontal beams 24 which are disposed under the floor 19. Secured to and projecting downwardly from the other end of the bar 20 is a second arm 25 which is preferably truly vertical. The lower end of this arm is slidably received between the beams 24, and a coiled compression spring 26 surrounds said arm between said beams and the bar 20, so as to normally hold the latter in engagement with the hook 17. 70 The parts 27 shown at the upper and lower ends of the spring 26, are merely washers. The beams 24 are suitably spaced apart to provide a vertical guide-way for the arms 22 and 25 whereby said arms will be guided and prevented from swinging laterally in their up and down movement between the beams. 75

At longitudinally spaced points, the bar 20 is provided with upwardly projecting studs 28 which pass through openings 29 in the floor 19. One of these studs is under the counter 11 and the other is preferably near a desk or table 30 within the cage. In case of danger, a person within the cage may depress either of the studs 28 and by so doing, he will swing the bar 20 to the position of Fig. 5, thus releasing it from engagement with the hook 17 and permitting the springs or the like 14 to immediately raise the bullet-proof barrier 13.

Preferably, we make use of a resilient cam 31 under the opening 18 to assist in engaging the hook 17 with the end 21 of the bar 20, whenever the barrier is again forced downwardly from its raised position.

In connection with the parts above described, we have illustrated an alarm 32 which may be at any desired location. By suitable wiring, this alarm is operatively connected with contacts 33 at the upper part of 100

the wall portion 10, and we have illustrated a switch plate 34 to bridge the gap between these contacts when the barrier 13 is raised as shown in Fig. 3. Thus, simultaneously with closing of the openwork wall portion 10, an alarm is sounded, with the intent of frightening the thieves or leading to their arrest, as may be desired.

Although the details disclosed may be followed if desired, it is to be understood that within the scope of the invention as claimed, variations may be made.

We claim:—

1. In a latch means for holding a sliding door depressed; a horizontally elongated bar beneath a floor and having one end to engage a door-carried member, an arm secured to said bar at said one end thereof and projecting downwardly therefrom, means pivotally mounting said arm for substantially horizontal swinging to effect substantially horizontal movement of said bar from engagement with the door-carried member, spring means acting on said bar for holding it normally engaged with the door-carried member, and a stud projecting upwardly from said bar through the floor, depression of said stud by foot serving to swing said bar and arm about the pivot of the latter to disengage said bar from the door-carried member.

2. In a latch means for holding a sliding door depressed, a horizontally elongated bar beneath a floor and having one end for engagement with a door-carried member, an arm secured to said bar at said one end thereof and projecting downwardly therefrom, means pivotally mounting said arm to permit swinging movement of said bar from engagement with the door-carried member, spring means acting on said bar for holding it normally engaged with the door-carried member, and a plurality of studs projecting upwardly from longitudinally spaced portions of said bar, said studs extending through the floor whereby depression of any stud by foot will swing said bar and arm about the pivot of the latter to disengage said bar from the door-carried member.

3. In a latch means for holding a sliding door depressed, a horizontally elongated bar beneath a floor and having one end to engage a door-carried member, an arm secured to said bar at said one end thereof and projecting downwardly therefrom, means pivotally mounting said arm to allow swinging movement of said bar from engagement with the door-carried member, a second arm secured to the other end of said bar and projecting downwardly therefrom, a stationary guide for said second arm, a spring surrounding said second arm for upwardly forcing said other end of said bar and holding said one end thereof engaged with the door-carried member, and a releasing stud projecting upwardly from said bar through the floor, depression of

said stud by foot serving to swing said bar and pivoted arm about the pivot of the latter to disengage said bar from the door-carried member.

4. In a latch means for holding a sliding door depressed, a pair of parallel horizontal beams secured beneath a floor and spaced apart horizontally to provide a guideway between said beams, a horizontally elongated bar under the floor above said guideway and having one end to engage a door-carried member, a substantially vertical arm secured at its upper end to said one end of the bar and projecting downwardly therefrom, means pivotally mounting the lower end of said arm in said guideway, a second arm secured to the other end of said bar and projecting downwardly therefrom into said guideway, both arms being guided by said guideway to prevent any lateral movement of the arms and the bar, a coiled compression spring surrounding said second arm for upwardly forcing said other end of said bar and holding said one end thereof engaged with the door-carried member, the lower end of said spring abutting the upper edges of said beams, and a releasing stud projecting upwardly through the floor from the bar.

In testimony whereof we have hereunto affixed our signatures.

DOMINICK LUSSETTO.
JAMES FASSERO.
